US00D469265S

(12) **United States Design Patent** (10) Patent No.: **US D469,265 S**
Holbrook et al. (45) Date of Patent: ** Jan. 28, 2003

(54) **CHAIR**

(75) Inventors: **Richard M. Holbrook**, Altadena, CA
 (US); **Darren M. Mark**, Valencia, CA
 (US)

(73) Assignee: **Virco Mgmt. Corporation**, Torrance,
 CA (US)

(**) Term: **14 Years**

(21) Appl. No.: **29/143,565**

(22) Filed: **Jun. 15, 2001**

(51) LOC (7) Cl. **06-01**

(52) U.S. Cl. **D6/366**

(57) **CLAIM**

The ornamental design for a chair, as shown and described.

DESCRIPTION

FIG. 1 is an isometric view showing the front side of a chair having features of the invention;

FIG. 2 is a isometric view of the chair illustrated in FIG. 1, showing the rear side of the chair;

FIG. 3 is a view of the left side of the chair illustrated in FIG. 1, the right side of the chair being a mirror image thereof with the exception of the adjustment lever;

FIG. 4 is a front view of the chair illustrated in FIG. 1; and, FIG. 5 is a rear view of the chair illustrated in FIG. 1.

1 Claim, 3 Drawing Sheets
